DESIGN FOR A KITCHEN CABINET OR SIMILAR ARTICLE

John R. Morgan, Oak Park, Ill., assignor to Sears, Roebuck and Co., Chicago, Ill., a corporation
of New York

Application April 27, 1938, Serial No. 76,767

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Kitchen Cabinet or Similar Article, of which the following is a specification, reference being had to the accompanying drawing, forming a part thereof.

The drawing is a perspective view of a kitchen cabinet or similar article embodying my new design.

The side not seen in the drawing is similar to the side which is shown.

I claim:

The ornamental design for a kitchen cabinet or similar article, as shown and described.

JOHN R. MORGAN.
